UNITED STATES PATENT OFFICE

LAWRENCE S. WILBUR, OF EVANSTON, ILLINOIS

METHOD OF CLEANING LUBRICATING WASTE OR PACKING

Application filed April 22, 1929. Serial No. 356,972.

This invention relates to the cleaning of lubricating waste, so that the waste can be used over again for lubricating the bearings of machinery, such as the stuffing boxes on railroad cars.

Generally stated, the object of the invention is to provide a novel and improved method and apparatus whereby the dirt is removed from the lubricating waste, in a comparatively inexpensive manner, and whereby the water is also removed, thus not only cleaning, but at the same time dehydrating, the lubricating waste, and thereby rendering it more suitable for further use.

It is also an object to provide certain details and features of construction and combinations and method steps tending to increase the general efficiency and the desirability of a method and apparatus of this particular character.

To the foregoing and other useful ends, the invention consists in the matters hereinafter set forth and claimed, and shown in the accompanying drawings, in which,—

Fig. 1 is a longitudinal section of a waste cleaning apparatus embodying the principles of the invention.

Fig. 2 is a vertical transverse section on line 2—2 in Fig. 1.

Fig. 3 is a fragmentary view of a portion of said machine.

Fig. 4 is a detail sectional view showing a different form of the invention.

As thus illustrated, the invention comprises a hopper like tank 1 formed of metal or other suitable material, with a square rectangular tank 2 at one end thereof. The tank 2 may rest on the floor, and the other end of the structure may be supported by legs 3 suitably secured thereto, as shown.

In the upper portion of the hopper like receptacle 1 there is a screen 4 adapted to receive the waste 5 therein. This screen is mounted on a transverse rock shaft 6, operated by a crank handle 7 and gearing 8 for tilting the screen 4 into upright position, as shown in dotted lines in Fig. 1 of the drawings. Another screen 9 is mounted in position as shown, adapted to receive the waste from the screen 4 when the latter is tilted

into upright position, after the waste has been washed and cleaned.

Air pipes 10 are arranged longitudinally in the upper portion of the tank 1, as shown, to blow air into the oil from the air jet openings 11 disposed along the sides of the pipes.

Heating pipes 12 are also arranged in the tank 1, as shown, in order that steam or hot water may be employed to heat the contents of the tank.

At the bottom of the tank 1, a screw conveyor 13 is longitudinally disposed therein, and arranged to discharge the dirt and sediment that accumulates at the bottom of the tank through the opening 14 into the bottom of the tank 2 previously mentioned. The latter has a clean-out opening 15 provided with a removable cover 16, whereby the accumulation can be cleaned out, and it may also be cleaned out from the open top of this tank. The shaft 17 of the screw conveyor 13 may be rotated by any suitable or desired means.

In operation, the dirty and more or less water-soaked lubricating waste 5 is placed in the screen 4, as shown. Oil 18 is employed in the two tanks, as shown, in order to wash out the water in the waste, and also a certain amount of the dirty oil, as well as the dirt and other foreign substance which may have accumulated in the waste. This oil 18 may be some lighter oil that will cut the lubricating oil of the waste, or it may be an oil very much like the lubricating oil itself. In any event, the body of oil in the two tanks is heated by the heating pipes 12 to the desired or required temperature, say from 170 to 200° Fahrenheit, depending somewhat upon conditions.

Air is then forced in through the pipes 10 and blown into the body of oil in the tank 1 of the apparatus. This air agitates the body of oil and bubbles up through the waste in the screen 4, thus washing out the sand and cinders and other foreign substance in the waste, causing the dirt and foreign substance to be precipitated to the bottom of the tank. The air also serves to dehydrate the waste, as it evaporates off any water that may have accumulated in the waste. When the waste is sufficiently cleaned and is sufficiently free

from water, it is tilted up and dumped into the screen 9, as previously explained.

Another advantage of this apparatus and method is the freedom from lint with which 5 the cleaned waste is discharged from the apparatus. New waste carries with it a considerable amount of lint, and the latter is objectionable in various ways, as it follows the lubricating oil and develops heat in the bearings. However, when the cleaned and dehydrated lubricating waste is discharged from 10 the apparatus shown and described, it is practically free from lint, as well as being free from dirt and water.

15 Of course, when the cleaned and dehydrated lubricating waste is discharged from the apparatus, it may then need some replenishment of the lubricating oil therein, and this can easily be done in the usual manner. 20 However, it will require much less oil and much less time to replenish the lubricating oil in waste of this kind than it would with entirely new and unused waste, inasmuch as the latter is dry when prepared, whereas this salvaged or reclaimed waste carries with it a certain percentage of lubricating oil when it is 25 discharged from the apparatus. It is even possible, of course, that by using a lubricating oil in the tanks, and by regulating the temperature of the heating means accordingly, the water and dirt can be taken out of the dirty waste in a manner to leave it sufficiently saturated with lubricating oil when it is discharged from the apparatus. This will all 30 depend, more or less, of course, upon the condition of the dirty waste to be cleaned.

In Fig. 4, the construction is similar to that shown in Fig. 2, but in this case the supporting screens 19 are arranged to sag 40 down between the air pipes 20 in the manner shown, so that the air will be injected directly into the lower portions of the masses of waste 21 supported on these screens.

In either form of the invention, however, 45 air is blown into the body of liquid to agitate the liquid and wash out the dirt and other foreign substance from the waste, as well as to dehydrate the waste.

Of course, the invention is not limited to 50 oil, as any hydrocarbon might be used, or some other liquid, depending upon the character of the product desired, so far as the method or process is concerned.

Furthermore, after the waste has been 55 washed out in the manner specified, it can then be put through a centrifugal wringer with any residual dirty oil therein to the extent desired. After that, the waste can then be put through a second washing or cleaning 60 apparatus, exactly like the one shown and described, but having a somewhat lighter oil therein, as for example, a gas oil for in effect rinsing the waste clean. After that, the waste can then be put through a centrifugal wringer again, and the desired quantity of

clean lubricating oil can then be added, the process and method insuring enough oil left in the waste to expedite the soaking in of the fresh oil.

What I claim as my invention is:

1. The method of cleaning lubricating waste, which comprises supporting the dirty waste in the upper portion of a body of oil or hydrocarbon, leaving the lower portion of said liquid clear, bubbling air up through the upper portion of the liquid and said waste, thus agitating the upper portion of the liquid and causing the precipitation of the dirt and foreign substance from the waste into the clear unagitated lower portion of said body of liquid, and removing the precipitated dirt from the unagitated bottom of said body of liquid. 70 75 80

2. A method as specified in claim 1, including the heating of said body of liquid, 85 by application of the heat below the air, keeping the temperature below the boiling point of the liquid, whereby to prevent foaming of the liquid.

3. A method as specified in claim 1, comprising the heating of said body of liquid, 90 by application of the heat below the air, keeping the temperature below the boiling point of water, thus facilitating the action of said air to dehydrate the waste while passing 95 upwardly through the latter.

Specification signed this 17th day of April, 1929.

LAWRENCE S. WILBUR.
